AERIAL ADVERTISING STREAMER

Edward Gustav Wiemer, Lynbrook, N. Y., assignor
to John J. Gilson, Jr., Lynbrook, N. Y.

Application January 8, 1934, Serial No. 705,798

9 Claims. (Cl. 40—127)

The present invention relates to aerial banners adapted to be towed through the air by an airplane or other aerial vehicle.

The present invention contemplates improvements in aerial banners according to which the body of the banner which carries the display matter is composed of a plurality of interchangeable sections, each including a plurality of parallel flat tapes adapted to form stringer members and a fabric letter, symbol, or the like extending across all the tapes and stitched to the tapes throughout the whole of their common extent.

According to the preferred construction these tapes extend beyond the fabric letter, symbol, or the like and provide means for securing the tapes of one section to the corresponding stringer members of adjacent sections. Each of the interchangeable sections is also preferably provided with a spacer bar disposed just in front of the leading edge of the fabric letter, or symbol and secured to each of the tapes.

The invention also contemplates that the banner be provided with additional tapes to be inserted between selected letters, so that words in the sign may be spaced to facilitate reading the banner.

A further object of the invention is to so design each of the component parts of a banner (of a predetermined height or width) that any part is capable of easy and interchangeable assembly to such other part or parts as required to make up a banner having a desired display.

Other features and advantages will become more readily apparent from the following description and drawings.

In the drawings, wherein like numerals are employed to designate like parts throughout the views:

Figure 1 is a side elevational view illustrating the complete streamer in flight, said streamer embodying the features and advantages of the present invention.

Figure 2 is an elevational view of a conventional airplane illustrating the manner in which the towline is releasably connected with the release means on the airplane.

Figure 3 is an elevational view of one of the interchangeable character or letter units on a larger scale than Figure 1.

Figure 4 is an elevational view of the front stretcher bar interposed between the bridle ropes and the leading letter unit.

Figure 5 is a perspective view of a windsock.

Figure 6 is an enlarged fragmentary detail view of a portion of one of the letter units or sections.

Figure 7 is an enlarged fragmentary sectional and elevational view of the rear stretcher bar to which the windsocks are detachably and swivelly connected.

Figure 8 is a similar view of the front stretcher bar shown in Figure 4.

Figures 9 and 10 are horizontal sections taken on the planes of the lines 9—9 and 10—10 of Figures 8 and 6 respectively.

Figure 11 is a horizontal section on the plane 10 of the line 11—11 of Figure 7.

Figure 12 is a similar sectional view taken on the plane of the line 12—12 of Figure 8.

Figure 13 is a detail view of a spacing strap.

Figure 14 is a detail elevational view of the trip cord actuated release device for the towline.

An airplane 15 having a fuselage 16 is provided with a trip cable 17 passing over a guide pulley 18 and connected to a pivoted bail or yoke 24 carried on a bracket 20. The bracket 20 has a pivoted mounting 21 for a latch 22, which normally extends into the bail or yoke 24, and it is held against accidental release by a spring 25. The latch also passes through a ring 23 carried at the front end of a towline 19.

The rear end of the towline 19 is connected to a ring 28 provided with ropes or cables 27 connected to rings 42 carried by a tubular stretcher bar 37. As shown in Figures 4, 8 and 9, these rings and bar are secured together by means of canvas or duck attaching bands 43 stitched, as indicated at 43^a and 43^b (Figures 8 and 9). Cotter pins 43^c prevent slippage. The stretcher bar 37 may be loaded with buckshot or equivalent weighting elements 38 sustained in place by plugs 39 and 40, so as to aid in maintaining the stretcher bar vertical.

The front stretcher bar 37 (as shown in Figures 4, 8 and 12) also carries a plurality of anchoring or attaching straps 41, each strap being formed out of a piece of fabric doubled about the bar 37, secured to the bar by a cotter pin 41^a and stitched, as indicated at 41^b and 41^c. These straps are in the same plane as the forwardly extending tabs 43. They extend rearwardly for the attachment of the body of the banner or streamer described generally by the reference character 26.

Considering now the specific construction of the streamer, it will be observed that this is composed of a plurality of appropriately co-ordinated companion units or sections 31 as shown in Figures 3, 6 and 10. These sections are properly standardized for interchangeable assembling in order to permit the sign to be made up on the 55

ground and changed from time to time to promote interest in the advertisement.

Each unit is the same in construction, and a description of one will suffice for all. As shown in Figures 3, 6 and 10 the unit or section is provided at the leading edge with a vertical rod or tube 32 and a plurality of canvas tapes 33 are connected thereto in horizontal parallel relationship with the same spacing as the attaching straps 41. As seen in Figure 10, the tapes are mounted on the rod adjacent one end so that to the left of the rod tabs 34 are formed, said tabs being stitched, as indicated by the dotted lines 34^a Figure 6, and serving to carry a disconnectible coupling device such as a spur-equipped buckle 35. The symbol or letter 36 is shown in Figure 3 as being preferably constructed from red bunting such as is used in flag construction, the same being stitched to the tapes 33 throughout the whole of their common extent, as indicated in the dotted lines 33^a and 33^b, Figure 6. The left-hand edge of the letter or symbol is in close proximity to the rod 32. The upper and lower stringers are fixedly secured to the rod 32 by cotter pins 33^c, as shown in Figure 6.

The forwardly extending tabs 34 on the first letter of the banner are readily attached to the straps 41 carried by the leading spreader bar, and the placing of the spreader bar or rod 32 of the section adjacent the leading edge of the fabric letter or symbol assists in the parting of the air stream as the banner is drawn forwardly in flight. As shown in Figures 1 and 3, the tapes 33 are of uniform length for each letter. The ends of the tapes 33 of a letter are readily attachable to the forwardly extending tabs of the succeeding letter unit or section. In flight the spreader bar of this section holds the rear ends of tapes 33 at the proper spacing, and the entire drag of the trailing portion of the banner is taken by the tapes. The letters are held flat against the tapes, and there is no slippage or looseness to cause chafing or wear, no sagging of the fabric relative to the tapes, and a minimum opportunity for the fabric of the letters to flutter.

The rear spreader bar 41 (shown in Figure 7) is similar to the front spreader bar 37, and may be loaded with shot as indicated at Figure 7. It carries forwardly extending short straps or tabs 52 provided with attaching devices such as buckles 53 for securement to the rear ends of the tapes 33 of the preceding section, such as the letter "D" in Figure 1. These straps are stitched, as indicated at 52^a, and secured in place on the tube or bar 41 by cotter pins 52^b. The rear spreader bar 41 also carries near each end a trailing strap 49 provided with a link 50 and swiveled snap hook 51. These straps are stitched, as indicated at 49^a, and are secured in place by cotter pins 49^b. The snap hooks 51 afford a convenient means for attaching cords 30 to which the wind socks 38 are secured.

Where a banner is to convey a message consisting of more than one word, the separation of these words to facilitate reading is highly desirable. This is readily accomplished in a banner made up from interchangeable sections by providing a requisite number of short straps 54 adapted for attachment to the rear ends of the stringers of one section (as by buckles 55) and to the forwardly extending tabs 34 of the succeeding section.

In some cases it may be desirable to provide diagonal bracing of the banner. This, as shown

in Figure 8, may be done by ropes 45 secured as indicated at 46, to tabs 44 carried by the spreader bars.

It is to be understood that minor changes in shape, size, relative proportions and materials 5 may be resorted to in practice without departing from the spirit of the invention or the scope of the invention as now claimed.

I claim:

1. An aerial advertising device of the class described comprising a plurality of substantially duplicate letter units separably connected together, each unit embodying a vertical spreader tube at one end, a plurality of spaced parallel tapes connected to said tube, the forward ends 10 of the tapes being formed at one end into tabs and said tabs being provided with disconnectible coupling means for securement to the rear end of the tapes of the preceding section, and a letter 15 stitched to the tapes throughout the whole of their common extent and disposed on one side of the tube.

2. An aerial advertising device of the class described comprising a longitudinally elongated flexible streamer embodying a plurality of letter units each including a plurality of spaced substantially parallel stringer members provided with disconnectible coupling means for securing corresponding stringers together and to which the material of the letter is secured, and a plurality 20 of stringer members adapted for installation in said streamer to serve as spacing elements to separate selected units from each other to facilitate legibility.

3. An aerial advertising banner comprising a 35 plurality of interchangeable sections, each section including a plurality of spaced substantially parallel flat tapes adapted to form stringer members, a fabric letter, symbol, or the like extending across all the tapes and being stitched 40 thereto throughout the whole of their common extent, the ends of the tapes extending therebeyond to provide means for securement of the section to the ends of the corresponding stringer members of adjacent sections, and disconnectible 45 coupling means for securing the corresponding stringers together.

4. An aerial advertising banner comprising a 50 plurality of interchangeable sections, each section including a plurality of spaced substantially parallel flat tapes adapted to form stringer members, a fabric letter, symbol, or the like extending across all the tapes and being stitched thereto throughout the whole of their common extent, the 55 ends of the tapes extending therebeyond to provide means for securement of the section to the ends of the corresponding stringer members of adjacent sections, a transversely extending spacer bar disposed adjacent the leading edge of the 60 letter or symbol and secured to each of the tapes, and disconnectible coupling means for securing the corresponding stringers together.

5. In an aerial banner, a leading stretcher bar, a plurality of forwardly extending tabs secured to the bar in fixed spaced relationship, bridle ropes detachably connected to each of the forwardly extending tabs, a plurality of rearwardly extending tabs secured to the bar in fixed spaced relationship, and in the same vertical 70 plane as the forwardly extending tabs, and a banner body having at the front end thereof a spacer bar, and a plurality of longitudinally extending letter carrying stringers, the stringers having at their front ends devices for readily dis- 75

connectibly connecting them to the rearwardly extending tabs.

6. A banner such as claimed in claim 5, wherein in each of the forwardly and rearwardly extending tabs is composed of a piece of strong fabric wrapped about the stretcher bar and stitched at its ends, so that the tab is two ply.

7. A banner such as claimed in claim 5, wherein the tabs extend about the stretcher bar and are secured thereto by transverse pins passing through the bar and the material of the tabs.

8. In an aerial banner, a normally vertical spreader bar, a fabric strap doubled on itself to

receive the rod, stitching passing through the double thickness of fabric to form a tab, and a transverse pin passing through the rod and fabric to hold the tab against longitudinal and rotary movement relative to the rod.

9. An aerial banner such as claimed in claim 8, wherein the doubled thickness of the strap also extends in a direction opposite the said tab to form a second tab, said second tab being stitched and a ring-like attaching device secured to the second tab so that tension may be transferred from one tab to the other.

EDWARD GUSTAV WIEMER.
